UNITED STATES PATENT OFFICE.

THOMAS A. JEBB AND LOUIS BRUSH, OF BUFFALO, NEW YORK, ASSIGNORS
TO THE AMERICAN DUPLEX-TICKET COMPANY, OF SAME PLACE.

IMPROVEMENT IN BOOKS OF RAILROAD FARE-TICKETS.

Specification forming part of Letters Patent No. 137,209, dated March 25, 1873.

To all whom it may concern:

Be it known that we, THOMAS A. JEBB and LOUIS BRUSH, both of the city of Buffalo, in the county of Erie and State of New York, have invented certain Improvements in Books of Railroad Fare-Tickets, of which the following is a specification:

Our improvements relate to books of fare-tickets for the use more especially of conductors and baggage-masters on railroads in the collection of cash fares and charges for excess baggage.

For a general description of these books and tickets, of the method of using them, and the advantages that result therefrom, reference is here made to Letters Patent of the United States No. 131,276 and No. 131,687, granted, respectively, to THOMAS A. JEBB on the 10th and 24th days of September, 1872.

These patents show and describe both single and double or duplex tickets, having stubs attached thereto, and bound in book form, both tickets and stubs being numbered consecutively alike, and having on each the number of the book. The tickets also contain the name of the road or section, the names of the stations, letters and figures representing the different months and days of the month, and a list of amounts of fare paid, arranged in a single or in duplicate columns. The two halves of the duplex tickets are printed in these respects in duplicate, while the books of single tickets have the lists of amounts paid printed on the stubs. The punch of each conductor using these kind of tickets makes its own peculiar-shaped perforation, so that the latter becomes in effect equivalent to the signature of the conductor, the perforation of any ticket being treated by the company as the signature of the conductor having the punch which makes the peculiar-shaped perforation shown in such ticket.

Books of both kinds of tickets are used for the same general purposes of preventing the fraudulent appropriation of fares by dishonest conductors, and to facilitate the making of correct returns by the conductors, and the keeping of correct accounts by the company with the conductors.

Our invention has for its object the more perfect accomplishment of the above-specified

purposes; and it consists, first, in books of duplex railroad tickets, a cover having delineated upon it the number of the book, and a system of dates, whereby a punch mark or marks will indicate the time of delivery to the conductor, or both the delivery and return thereof, so that the return of the book or its detached cover, punched, operates as a record of the transaction as between the ticket-agent and conductor; second, in such a book, the two covers carrying the data above referred to, whereby one punched and detached cover operates as a receipt therefor, while the attached cover, punched, when returned, operates as a balancing credit.

In the accompanying drawing, Figure 1 is a perspective view of a book of tickets, showing an outer-face view of the front cover. Fig. 2 is a similar view of the book, showing the front cover detached. Fig. 3 is a view showing the stubs after the front cover and tickets have been detached, and inner-face view of the back cover.

The drawing represents cash-fare passenger-tickets adapted for use between Rochester and Niagara Falls on the New York Central and Hudson River Railroad, which tickets are further designated as "Form 8," and are of substantially the same character as those described in said Letters Patent No. 131,276, and are designed to be used in the same general and now well-known way.

The front and back covers are preferably and most conveniently printed with the same matter and type as the tickets themselves, except that the covers are not numbered otherwise than with the number of the book.

Fig. 1 represents the front cover, with the date, "January 4th," punched out, which indicates that the book was delivered on that day to the conductor having a punch which makes the peculiar form of perforation shown in the cover. This cover being detached and left at the office, the book is in the shape shown in Fig. 2, and ready for convenient use, the first ticket being numbered "1." The tickets are required to be issued in the order of the numbers as they are in the book, and when all are issued the stubs and cover, in the condition shown in Fig. 3, are to be returned to the office of the company, and the date of such re-

turn punched out of the back cover, the drawing indicating "January 10th" as the date of such return. The dates of delivery and return being indicated in this manner on the book itself by the conductor or other person issuing or using the tickets, they cannot be altered or the correctness thereof questioned.

The printed cover greatly facilitates the selection of any particular kind of book that may be required for delivery. It will be seen that a single cover may be used, as, the date of the delivery being anterior to the return, occasion for the use of characters already punched is not likely to occur, but it may be deemed less safe to trust the receipt in the hands of the conductor; and to overcome any such objection I provide two covers to be used as described, so that the moment the book is delivered one cover punched is torn off and retained at the office as a receipt, while the other on the return of the book is punched, and acts as a credit to the conductor.

It is manifest that our improvements are equally applicable to books of single tickets

as to books of duplex tickets, and to books of tickets adapted for use on bridges, steam-boats, &c., as well as on railroads.

We claim as our invention—

1. In books of duplex railroad tickets, a cover having delineated upon it the book number and a system of dates, whereby a punch mark or marks will indicate the time of delivery or both the delivery and return, and the detached cover thus punched operates as a record of the transactions, as between the agent and conductor, substantially as herein-before set forth.

2. In such a book, the two covers carrying the data above set forth, whereby one punched and detached cover operates as a receipt therefor, and the other attached cover as a credit for its return, substantially as herein-before set forth.

T. A. JEBB.
LOUIS BRUSH.
